Primary Examiner — Cathy Anne MacCormac(74) *Attorney, Agent, or Firm* — Dunlap Bennett & Ludwig PLLC(57) **CLAIM**

The ornamental design for a pet highchair, as shown and described.

DESCRIPTION

FIG. 1 is a top front perspective view of the pet highchair; FIG. 2 is a front elevation view of the pet highchair, with the rear elevation view being identical to the front view shown; FIG. 3 is a right side elevation view of the pet highchair, with the left side elevation view being identical to the front view shown;

FIG. 4 is a top plan view thereof; and,

FIG. 5 is a bottom plan view thereof.

The broken lines shown in the drawings depict environmental subject matter and form no part of the claimed design. The pet highchair is shown with a line-dot-line broken line which represents a symbolic break in its height. The appearance of any portion of the article between the break lines forms no part of the claimed design.
